UNITED STATES PATENT OFFICE

CHARLES ARTHUR MAHER, OF OTTAWA, ILLINOIS

EYE-CUP.

Specification of Letters Patent.

Patented March 2, 1909.

No. 914,295.

Application filed September 17, 1906. Serial No. 334,954.

To all whom it may concern:

Be it known that I, CHARLES ARTHUR MAHER, a citizen of the United States, residing at Ottawa, in the county of Lasalle and State of Illinois, have invented a new and useful Eye-Cup, of which the following is a specification.

This invention relates to means for introducing medicines, washes, and the like into the eye, and the principal object is to provide a simple and novel article of manufacture, which will insure the proper application of the desired material to the eye, and will keep it thereon and therein as long as desired, said article of manufacture furthermore being so constructed that medicament may be taken from a bottle and introduced into the eye without exposure to the outside air.

The preferred form of construction is illustrated in the accompanying drawings, wherein:

Figure 1 is a side elevation of the device. Fig. 2 is a sectional view therethrough. Fig. 3 is a bottom plan view.

Similar reference numerals designate corresponding parts in all the figures of the drawings.

In the embodiment illustrated, the article consists of an eye covering cup, a compressible bulb having a conduit, and a nipple constituting an extension of the conduit and located in the cup, all these parts being formed integral one with the other and of soft compressible material, preferably rubber.

The cup, designated 4 in the drawings, is substantially elliptical in shape having an open eye receiving side, the edges of the side walls 5, which surround said open side, being curved, as shown at 6. A rear wall 7 closes the rear side of the cup, and thus an interior chamber 8 is formed. The bulb, designated 9, has an integral conduit 10 extending therefrom, said conduit projecting through the rear wall 7 and into the chamber forming an integral compressible nipple 11 that is tapered. It will be observed that the free end of the nipple terminates short of the curved edges 6 of the cup, and if desired, a suitable nozzle 12 may be fitted thereto.

In using the device, the nipple 11 is fitted tightly into the mouth of a bottle or vial, said bottle or vial and the eye cup attached thereto being inverted, the bulb 9 is compressed to expel the air therefrom. Upon being released, it will be evident that the medicament in the bottle or vial will be drawn into

the bulb and conduit. The cup is then fitted to the eye and is compressed in order to cause a partial vacuum in the chamber 8. Said cup having been positioned, the bulb 9 is again compressed, thus discharging the medicament and applying it to the eye. As long as the cup is maintained in position, the medicament will be retained within the chamber 8, and thus its proper application is assured.

An article of manufacture, as thus produced, is very simple and has proven to be exceedingly efficacious. By employing soft rubber, the nipple will be compressed in the neck of the bottle when applied thereto, preventing leakage and permitting the complete emptying of the bottle. Furthermore the eye cup and the bulb are separately and independently compressible so that the application of the former to the eye will not affect the latter, and the discharging operation afforded by the compression of the bulb is independent of the application of the cup to the eye. Moreover, inasmuch as the medicament can be withdrawn directly from the bottle or vial into the conduit and bulb and discharged therefrom directly into the eye, it will not come into contact with the atmosphere.

A further and very important feature of the invention is the compressible eye cup. The reason for employing a compressible cup is that when compressed and applied to the eye, it will effectively prevent the eyelids from closing, thus insuring the perfect application of the medicament or wash to the surface or coat of the eye. One of the very serious objections to applying washes or medicament to the human eye, is the difficulty in keeping the eye open to receive the same. This device entirely eliminates the difficulty.

Having thus fully described my invention, what I claim as new, and desire to secure by Letters Patent, is:

1. As an article of manufacture, an eye cup substantially elliptical in form and having an open eye receiving side and a rear wall, a compressible bulb having a conduit that extends through said rear wall and terminates in a short tapered nipple within the eye cup, said cup, bulb, conduit and nipple being formed integrally of soft compressible material, the cup and bulb being independently compressible, and the former having the edges, surrounding the open side, curved to conform substantially to the parts to which

it is applied, and said nipple constituting a compressible stopper adapted to be inserted into the neck of a bottle or vial.

2. As an article of manufacture, an eye cup substantially elliptical in form, and having the front wall open to receive the eye, and a closed rear wall, a compressible bulb having a conduit that extends through said rear wall, said cup and bulb being formed integrally of soft compressible rubber, the cup and bulb being independently compressible, and the cup having the edges of the sides at

the front curved to conform substantially to the part to which the cup is applied, whereby the medicament may be introduced into the cup after the latter has been compressed and applied to the eye. 15

In testimony, that I claim the foregoing as my own, I have hereto affixed my signature in the presence of two witnesses.

CHARLES ARTHUR MAHER.
